(57) **CLAIM**

The ornamental design for a cosmetic compact, as shown and described.

DESCRIPTION

FIG. 1 is a top, front and right side perspective view of my new design for a cosmetic compact, shown in the closed position;

FIG. 2 is a front elevation view of the cosmetic compact, shown in FIG. 1;

FIG. 3 is a rear elevation view of the cosmetic compact, shown in FIG. 1;

FIG. 4 is a right side elevation view of the cosmetic compact, shown in FIG. 1;

FIG. 5 is a left side elevation view of the cosmetic compact, shown in FIG. 1;

FIG. 6 is a top plan view of the cosmetic compact, shown in FIG. 1;

FIG. 7 is a bottom plan view of the cosmetic compact, shown in FIG. 1;

FIG. 8 is a right side perspective view of the cosmetic compact, shown in FIG. 1, in an open position; and,

FIG. 9 is a right side elevation view of the cosmetic compact, shown in FIG. 8.

The broken lines, shown in FIG. 8, depict portions of the cosmetic compact which form no part of the claimed design.

1 Claim, 5 Drawing Sheets
